SMOKING PIPE

Stephen P. Chernock, 1553 Boston Post Road,
Milford, Conn. 06460

Filed Apr. 22, 1966, Ser. No. 1,985

Term of patent 14 years

(Cl. D85—8)

FIG. 1 is a perspective view of a smoking pipe, showing my new design;

FIG. 2 is a side elevation;

FIG. 3 is a top plan view;

FIG. 4 is a bottom plan view;

FIG. 5 is a front elevation;

FIG. 6 is a transverse sectional view, taken along the line 6—6 of FIG. 2; and

FIG. 7 is a transverse sectional view, taken along the line 7—7 of FIG. 2.

The characteristic feature of my design resides in the laterally extending longitudinal flanges at each side of the central thin tubular shank of the stem, the flanges having straight outer edges parallel to the tubular shank and provided with laterally aligned single rows of longitudinally spaced elongated slots arranged in parallel relation between the tubular shank and said straight outer edges.

I claim:

The ornamental design for a smoking pipe, substantially as shown and described.
